UNITED STATES PATENT OFFICE.

BERNARD LEVY, OF PHILADELPHIA, PENNSYLVANIA, ASSIGNOR TO THE KEYSTONE WATCH CASE CO., OF RIVERSIDE, NEW JERSEY, A CORPORATION OF PENNSYLVANIA.

DESIGN FOR A WATCHCASE.

Application filed May 12, 1926. Serial No. 17,668. Term of patent 3½ years.

To all whom it may concern:

Be it known that I, BERNARD LEVY, a citizen of the United States, residing at Philadelphia, in the county of Philadelphia and State of Pennsylvania, have invented a new, original, and ornamental Design for Watchcase, of which the following is a specification, reference being had to the accompanying drawing, forming part thereof.

In the drawing, Fig. 1 is a plan view of a watch case, showing my new design, and Fig. 2 is an edge view thereof.

I claim:

The ornamental design for a watchcase, as shown.

BERNARD LEVY.
